US0D1095542S

(12) **United States Design Patent** (10) **Patent No.:** **US D1,095,542 S**
(45) **Date of Patent:** **** Sep. 30, 2025**

(54) **KEYBOARD WRIST REST**

(71) Applicant: **Jia Zhang**, Nanchong (CN)

(72) Inventor: **Yangyan Zhuo**, Shaoguan (CN)

(73) Assignee: **Jia Zhang**, Nanchong (CN)

(**) Term: **15 Years**

(21) Appl. No.: **29/992,779**

(22) Filed: **Mar. 11, 2025**

(51) LOC (15) Cl. **06-06**

(52) U.S. Cl.

USPC **D14/461**

(57) **CLAIM**

The ornamental design for a keyboard wrist rest, as shown and described.

DESCRIPTION

FIG. 1 is a top, front and left side perspective view of a keyboard wrist rest showing my new design;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plan view thereof; and,

FIG. 7 is a bottom plan view thereof.

1 Claim, 7 Drawing Sheets
